Des. 203,436
Patented Jan. 11, 1966

203,436

SALT BLOCK

Daniel M. Conway, Crystal Lake, Ill., and Sherman S. Martin, South Salt Lake City, Utah, assignors to Morton Salt Company, Chicago, Ill., a corporation of Delaware

Filed Apr. 30, 1964, Ser. No. 79,752

Term of patent 14 years

(Cl. D12—2)

FIG. 2 is an enlarged top plan view of said salt block;

FIG. 3 is an enlarged bottom plan view of said salt block; and

FIG. 4 is an enlarged side elevation of the salt block of FIG. 1.

We claim:

The ornamental design for a salt block, substantially as shown.
